ABSTRACT

An apparatus equipped to receive power from a wall outlet power source. The apparatus includes a plurality of outlets capable of extending a predetermined distance apart for distributing a power input from such wall outlet power source to at least one pre-selected object electrically connected to one of the plurality of outlets. The electrical outlet apparatus comprises a first electrical plug receptacle engageable in and electrically connected to such wall outlet power source. A number of additional electrical plug receptacles are arranged in a predetermined pattern and electrically connected to receive electrical power from the first electrical plug receptacle. There is a mechanism engageable at a predetermined location with each of such predetermined number of electrical plug receptacles for spacing them a predetermined distance apart to facilitate insertion and removal of plugs attached to such pre-selected objects. Such mechanism is capable of expanding and retracting such electrical plug receptacles.

EXPANDABLE ELECTRICAL PLUG

CROSS REFERENCE TO RELATED
APPLICATIONS

This application is related to and claims priority from Provisional Patent Application Ser. No. 60/885,244 filed Jan. 17, 2007, Provisional Patent Application Ser. No. 60/885,245 filed Jan. 17, 2007 and Provisional Patent Application Ser. No. 60/871,163 filed Dec. 21, 2006.

FIELD OF THE INVENTION

The present invention relates, in general, to electrical wall outlets and electrical cords having at least one plug connection for plugging an electrically operated device into and, more particularly, this invention relates to an expandable electrical plug connector for plugging a plurality of such electrically operated devices therein.

BACKGROUND OF THE INVENTION

Prior to the conception and development of the present invention, as is generally well known in the art, electrical wall plugs and extension cords have been in widespread use to provide power to electrical devices.

As is equally well recognized, these electrical wall plugs and extension cords have outlets which are oftentimes spaced relatively close together. Such closely spaced outlets can make it quite difficult at times to plug in more than one device at a time in some wall outlets and/or extension cords because the outlets are normally spaced relatively close together. This is particularly the case with certain types of plugs attached to the device. These plugs come in a large variety of sizes and shapes. Examples of these devices at least include, but are not limited to, kitchen appliances, lamps, audio equipment, television, radio, alarm clocks, electric razors, hair dryers, etc.

Even if one is able to plug more than one plug into an electrical outlet it may be quite difficult to remove the plug due to their close proximity to one another. Although in building a new structure such as a home or commercial building it is possible to provide sufficient outlets to alleviate the above identified problem it is not likely that a building will be rewired just for this problem alone.

SUMMARY OF THE INVENTION

The present invention provides an electrical outlet apparatus equipped to receive power from an electrical receptacle of a wall outlet power source. The electrical outlet apparatus includes a predetermined plurality of outlets capable of extending a predetermined distance apart for distributing a power input from such wall outlet power source to at least one pre-selected object electrically connected to one of such predetermined plurality of outlets. The electrical outlet apparatus includes a first means engageable in and electrically connected to such wall outlet power source for supplying power to such apparatus. A predetermined number of electrical plug receptacles are arranged in a predetermined pattern and are electrically connected to receive electrical power from such first electrical plug receptacle engaged in such wall outlet power source. There is a second means engageable at a predetermined location with each of such predetermined number of electrical plug receptacles for spacing them a predetermined distance apart to facilitate insertion and removal of plugs attached to such pre-selected

2

objects. Such second means is capable of expanding and retracting the predetermined number of such electrical plug receptacles.

5 OBJECTS OF THE INVENTION

It is, therefore, one of the primary objects of the present invention to provide an electrical outlet apparatus having a predetermined number of outlets to receive an electrical plug therein which is capable of being arranged in a predetermined manner.

Another object of the present invention is to provide an electrical outlet apparatus having a predetermined number of outlets to receive an electrical plug therein which enables the outlets to be spaced apart to facilitate insertion and removal of electrical plugs attached to preselected objects.

Still another object of the present invention is to provide an electrical outlet apparatus having a predetermined number of outlets to receive an electrical plug therein which can be produced in designer colors.

Yet another object of the present invention is to provide an electrical outlet apparatus having a predetermined number of outlets to receive an electrical plug therein which can be produced as an extension cord type device.

An additional object of the present invention is to provide an electrical outlet apparatus having a predetermined number of outlets to receive an electrical plug therein which is relatively easy to use.

30 In addition to the various objects and advantages of the present invention described with some degree of specificity above it should be obvious that additional objects and advantages of the present invention will become more readily apparent to those persons who are skilled in the relevant art from the following more detailed description of the invention, particularly, when such description is taken in conjunction with the attached drawing figures and with the appended claims.

40 BRIEF DESCRIPTION OF THE DRAWINGS

FIG. 1 is a plan view of a presently preferred embodiment of an extension cord type device having a plurality of electrical outlets shown in a closed position;

45 FIG. 2 is a plan view of the extension cord type device having a plurality of electrical outlets illustrated in FIG. 1 and shown in an open position;

FIG. 3 is a plan view of an electrical receptacle engageable in a wall outlet produced according to the present invention and shown in a closed position;

FIG. 4 is a plan view of the electrical receptacle engageable in a wall outlet illustrated in FIG. 3 and shown in an open position;

55 FIG. 5 is a plan view of an alternative embodiment of an electrical receptacle engageable in a wall outlet produced according to the present invention and shown in a closed position; and

FIG. 6 is a plan view of the electrical receptacle engageable in a wall outlet illustrated in FIG. 5 and shown in an open position.

FIG. 7 is a plan view of the extension cord type device having a plurality of electrical outlets illustrated in FIG. 1 and shown in an open position.

65 FIG. 8 is a plan view of the electrical receptacle engageable in a wall outlet illustrated in FIG. 5 and shown in an open position.

BRIEF DESCRIPTION OF A PRESENTLY
PREFERRED AND VARIOUS ALTERNATIVE
EMBODIMENTS OF THE INVENTION

Prior to proceeding to the more detailed description of the present invention it should be noted that, for the sake of clarity and understanding, identical components which have identical functions have been identified with identical reference numerals throughout the several views illustrated in the drawing figures.

Reference is now made, more particularly, to FIGS. 1-6. Illustrated therein are the presently preferred and a number of alternative embodiments of an electrical outlet apparatus, generally designated 10 in FIGS. 1 and 2 and generally designated 20 in FIGS. 3-6, equipped to receive power from an electrical receptacle of a wall outlet power source 11.

In FIGS. 1 and 2, the apparatus 10 is illustrated as an extension cord 12 whereas in FIGS. 3-6 the apparatus 20 is illustrated as a wall plug 14.

In either case, such electrical outlet apparatus 10, 20 has a predetermined plurality of outlets 16 capable of extending a predetermined distance apart for distributing a power input from such wall outlet power source to at least one pre-selected object (not shown) electrically connected to one of such predetermined plurality of outlets 16.

The electrical outlet apparatus 10, 20 will include a first means, generally designated 30, which is engageable in and electrically connected to such wall outlet power source for supplying power to such apparatus 10, 20. In the case of the extension cord 12, such first means 30 is a plug 18.

There are a predetermined number of electrical plug receptacles 16, arranged in a predetermined pattern, which are electrically connected to receive electrical power from such first electrical plug receptacle 16 engaged in such wall outlet power source 11. In the case of the apparatus 20, such first means 30 is one of such predetermined number of electrical plug receptacles 16 that can be plugged into such wall outlet power source 11.

A second means, generally designated 40, engageable at a predetermined location with each of such predetermined number of electrical plug receptacles 16 for spacing them a predetermined distance apart to facilitate insertion and removal of plugs (not shown) attached to such pre-selected objects (not shown). Such second means 40 is capable of expanding and retracting the predetermined number of said electrical plug receptacles 16. In the presently preferred embodiment of the invention such predetermined distance such electrical plug receptacles 16 are spread apart is generally up to about 4.0 inches. Additionally, the second means 40 includes retaining means 24 for retaining such receptacles 16 apart and a retraction means 26 for retracting such receptacles 16. Such retraction means 26 is preferably a spring and specifically a tension spring.

In the present invention there will be at least three receptacles 16. More preferably there will be between three and six receptacles 16. The presently preferred predetermined pattern is one of linear and a pattern containing at least one row and at least one column of receptacles.

Further, in the presently preferred embodiment for both the apparatus 10 and 20 each of the receptacles 16 will include a ground 28. Also, the extension cord 12 includes an on/off type switch 32.

FIGS. 7 and 8 illustrate the extension cord type device 10 and the electrical receptacle engageable in a wall outlet type device 20 each in an open position. Less than all outlets 16 in both the extension cord type device 10 and the electrical receptacle engageable in a wall outlet type device 20 as

illustrated in FIG. 2 and its alternative embodiment as illustrated in FIG. 5 can be extended without extending all of the other outlets 16.

While a presently preferred and various alternative embodiments of the present invention have been described in sufficient detail above to enable a person skilled in the relevant art to make and use the same it should be obvious that various other adaptations and modifications can be envisioned by those persons skilled in such art without departing from either the spirit of the invention or the scope of the appended claims.

I claim:

- An electrical outlet apparatus equipped to receive power from an electrical receptacle of a wall outlet power source, said electrical outlet apparatus having a predetermined plurality of outlets capable of extending a predetermined distance apart for distributing a power input from such wall outlet power source to at least one pre-selected object electrically connected to one of said predetermined plurality of outlets, said electrical outlet apparatus comprising:
  - a first means engageable in and electrically connected to such wall outlet power source for providing power to said electrical outlet apparatus;
  - a predetermined number of electrical plug receptacles, arranged in a predetermined pattern, electrically connected to receive electrical power from said first means engaged in such wall outlet power source; and
  - a second means engageable at a predetermined location with each of said predetermined number of said electrical plug receptacles for spacing them a predetermined distance apart to facilitate insertion and removal of plugs attached to such pre-selected objects, said means capable of expanding and retracting said predetermined number of said electrical plug receptacles.
- An electrical outlet apparatus, according to claim 1, wherein said apparatus is formed as an extension cord type device.
- An electrical outlet apparatus, according to claim 2, wherein said first means is a plug.
- An electrical outlet apparatus, according to claim 1, wherein said apparatus is formed as an electrical wall plug type device.
- An electrical outlet apparatus, according to claim 1, wherein said predetermined distance by which said electrical plug receptacles are spread apart is generally up to about 4.0 inches.
- An electrical outlet apparatus, according to claim 1, wherein said second means includes retaining means for retaining said receptacles apart and a retraction means for retracting said receptacles.
- An electrical outlet apparatus, according to claim 6, wherein said retraction means is a spring.
- An electrical outlet apparatus, according to claim 7, wherein said spring is a tension spring.
- An electrical outlet apparatus, according to claim 1, wherein said predetermined number of electrical plug receptacles is at least three.
- An electrical outlet apparatus, according to claim 1, wherein said predetermined number of electrical plug receptacles is between about three and six.
- An electrical outlet apparatus, according to claim 1, wherein said predetermined pattern is linear.
- An electrical outlet apparatus, according to claim 1, wherein said predetermined pattern includes at least one row and at least one column of receptacles.

13. An electrical outlet apparatus, according to claim 1, wherein each of said receptacles include a ground.

14. An electrical outlet apparatus, according to claim 2, wherein said extension cord includes an on/off type switch.

15. An electrical outlet apparatus, according to claim 3, wherein only one of said predetermined number of said electrical plug receptacles can be plugged into such wall outlet power source.

16. An electrical outlet apparatus, according to claim 1, wherein said predetermined pattern includes moving any predetermined number of said electrical plug receptacles apart while leaving others together.

17. An electrical outlet apparatus, according to claim 2, wherein said predetermined pattern includes moving any

predetermined number of said electrical plug receptacles apart while leaving others together.

18. An electrical outlet apparatus, according to claim 11, wherein said predetermined pattern includes moving any predetermined number of said electrical plug receptacles apart while leaving others together.

19. An electrical outlet apparatus, according to claim 12, wherein said predetermined pattern includes moving any predetermined number of said electrical plug receptacles apart while leaving others together.
